AUTOMATIC REVERSING MECHANISM

Anthony J. Phillips, Lower Southampton Township, Bucks County, Pa.

Application August 26, 1933, Serial No. 686,903

1 Claim. (Cl. 74—59)

My invention relates to new and useful improvements in an automatic reversing mechanism, and has for one of its objects to provide a mechanism which may be utilized for operating different types of oscillating mechanisms from a revolving shaft which continuously revolves in one direction.

Another object of the invention is to generally improve the construction of baling presses to provide an exceedingly simple and effective device of this character that will be relatively inexpensive in the cost of manufacture although strong and durable and efficient in operation.

Another object of the invention is to provide a mechanical movement in which the direction of rotation of one or more driven shafts may be alternately reversed and the driven shaft or shafts made to oscillate other elements although the driving shaft continues to revolve in one direction.

A still further object of the invention is to provide unique means instituting the reverse movements of the driven devices.

With these and other ends in view, this invention consists in the details of construction and combination of elements hereinafter set forth and then specifically designated by the claim.

In order that those skilled in the art to which this invention appertains may understand how to make and use the same, I will describe its construction in detail, referring by numerals to the accompanying drawings forming a part of this application, in which:—

Fig. 1 is a top plan view of a baling press embodying my improvements.

Fig. 2 is a view with the plunger housing and plunger shown in section on the longitudinal center thereof with the end of the housing for the mechanical movement and one of the side walls of the press removed and also parts of the plunger and the axle of the reversing mechanism broken away.

Fig. 3 is an enlarged longitudinal sectional view of the driving mechanism.

Fig. 4 is a forward or inner end view of the baling press with a wall of the mechanism housing removed.

Fig. 5 is an enlarged plan view of the reversing cam showing its relation to the reversing axle.

Fig. 6 is a side elevation or edge view thereof with a section of the shaft having parts broken away.

Fig. 7 is an end view thereof.

In carrying out my invention as herein embodied, 10 represents the base plate of the press

provided at the forward or inner end with a head plate 11 running crosswise of said base plate. This base plate supports longitudinal side plates or walls 12 forming a slide for the baling plunger and with a top plate 13 at the outer end provides a compartment 14 in which the material to be bailed is pressed and to said compartment leads a suitable hopper 15. Said base plate 10 and the head plate 11 also support a front plate or wall 16 and a rear plate or wall 17, and if found desirable, end plates or walls 18 may be provided so as to form an enclosure for the operating mechanism.

In the mechanism housing running longitudinally thereof so as to be crosswise of the plunger chamber is located a polygonal shaft 19 carrying suitable journals 20 whereby the shaft may be revolvably mounted in the split bearings 21 supported by cross pieces 22 in the mechanism housing.

On the shaft intermediate the ends thereof are mounted a pair of opposed sleeves 23 and 24, each having a flange at its outer end to prevent outward longitudinal movement of its respective bevel gear mounted to revolve on the sleeve. 25 There are two such bevel gears 25 and 26 and they mesh with one or more bevel pinions 27 and 28. The bevel gears being in mesh with a bevel pinion or pinions will be held against inward longitudinal movement. The sleeves are 30 held against movement relative to the shaft 19 by suitable fastenings, such as screws 29. The gears 25 and 26 are provided with clutch elements 30 to be engaged by clutch elements 31 carried by the clutch members 32 and 33 mounted on the 35 shaft 19 to revolve therewith as well as slide thereon. The sliding movements of the clutch members enable them to be moved into or out of engagement with their respective bevel gears in order to cause either of said gears to revolve 40 with the shaft while the other is free to be revolved independently of the shaft.

The clutch members are provided with annular grooves 34 to receive the forks 35 of the reversing mechanism and said forks are secured on the 45 ends of a longitudinally sliding rod 36 by nuts 37 screwed on to the threaded ends of said rod. Said rod 36 is slidably mounted in suitable spaced supports 38 and said rod is provided with a finger 39 to which is connected one end of a link 40 while the other end of said link is attached to a crank 41 as at 42 and this crank is mounted upon one end of a rotating axle 43. The crank 41 is of such length that when the axle 43 is rotated approximately one-half turn the clutch mem- 50 55

bers will be moved a complete stroke, one being moved into working position and the other out of working position, thereby placing the link 40 on a dead center line each time a complete movement is made for locking the parts against accidental movement.

On the axle 43 are mounted a pair of arms 44 and 45 in proper spaced relation for coaction with a cam device which will rotate the axle, all 10 of which will be presently described.

One of the bevel pinions, as 27, is mounted upon a screw shaft 46, suitably journalled, as in the wall 17 and said screw shaft is held against longitudinal movement by collars 47 or other 15 equivalent means. In one instance, the equivalent means might be the hub of the bevel pinion 27. The threaded portion 48 of the screw shaft has threaded connection with the rear wall 49 of the plunger 50 mounted to slide on tracks 20 51 carried by the side plates or walls 12 and snugly fitting the plunger compartment. It may only be necessary to actually guide the rear part of the plunger and for this reason the upper end of the rear wall 49 of said plunger is shown as 25 provided with an extension 52 in the side edges of which are formed the guide grooves for registration with said tracks 51.

The plunger is moved to and fro in its chamber in a manner that its nose may enter the compartment 14 for compressing material in said compartment prior to being tied into a bale.

On the plunger and more particularly on the wall 49 is mounted a cam device 53 including a bracket 54 and two cam elements 55 and 56 35 so shaped that when either one engages the proper arm 44 and 45 the latter will be caused to travel in a half circle during the time the cam travels a distance equal to that between its ends whereby the axle 43 will be given a one-half turn in one direction.

To the plunger 50 is pivoted one end of a pitman 57 as at 58 while the other end of said pitman is pivoted as at 59 to an oscillating beam 60 pivoted intermediate its ends on an axle 61, 45 the ends of which are mounted in uprights 62 which may be secured to the side plates or walls 12. The beam 60 is so pivoted that it has a short end and a long or outer end and the outer end carries a tamp 63 which is projected through 50 the hopper 15 into the compartment 14 each time the plunger 50 is moved away from said hopper.

In practice the operation of the device is as follows:—

With the parts in the positions illustrated herein, the teeth of the clutch member 33 are in engagement with the teeth of the gear 26 wherefore power is being transmitted from the driving shaft 19 through the clutch member 33, gear 26, pinion 27 and screw shaft 46 so that the plunger 50 is being retracted or withdrawn from the compartment 14. At the time this backward movement is being imparted to the plunger, motion will be transmitted to the beam 60 through the pitman 57 to project the tamp 63 through the hopper 15 into the compartment 14 and any material in said compartment 14 below the opening of the hopper will be depressed so as to be free from the hopper through which it was fed into the compartment 14.

Since the plunger 50 carries the cam device 53 therewith at a certain point in the backward movement of said plunger, the cam member 55 will engage the arm 45 and cause it to rotate from its present upstanding position to a depending position relative to the axle 43 thereby rotat-

ing said axle so as to impart movement through the crank 41 and link 40 to the sliding rod 36, thereby moving the forks 35 so as to disengage the clutch member 33 from the gear 26 and simultaneously engage the clutch member 32 with the gear 25. 5

This will cause motion to be imparted from the shaft 19 through the clutch member 32 and gear 25 to the pinion 27, thereby reversing the direction of rotation of said pinion 27 without changing the direction of rotation of the shaft 19. It might be well to state at this time that when one gear is driving the pinion 27 the companion gear is free to revolve on the sleeve 23. This reversal in the direction of rotation of the pinion 27 will, 15 of course, reverse the direction of rotation of the screw shaft 46, thereby moving the plunger 50 forward toward and into the compartment 14 for forcing or compressing the material which has been depressed by the tamp toward the far 20 end of the compartment 14.

During the above last mentioned operation, motion will be transmitted through the pitman 57 to the beam 60 to lift the outer longer end thereof so as to withdraw the tamp 63 from the 25 compartment 14 and out of the path of travel of the plunger 50. At a certain location during the forward movement of the plunger 50, the cam element 55 will engage the arm 44 which is now in upright or elevated position and move said arm into the depending position as shown in Fig. 2, which will then again reverse the driving mechanism in order to place the parts in the positions herein illustrated.

The reversing movements may be accomplished 35 at desired locations in the movements of the plunger by changing the positions of the arms 44 and 45 on the axle 43 and for this purpose I have shown said arms as slidably mounted on the axle 40 to be held in any adjusted positions by screws 64.

As before suggested, any number of pinions that can be accommodated can be mounted between the gears 25 and 26 and as an illustration thereof I have shown a second pinion 28 which is mounted upon a shaft 65 running off in some direction other than that taken by the screw shaft 46 and of course said shaft 65 will be reversed each time the screw shaft is reversed but it may be used for any other suitable reciprocating or oscillating mechanism.

Of course I do not wish to be limited to the exact details of construction herein shown and described as these may be varied within the limits of the appended claim without departing from the spirit of my invention.

Having thus fully described my invention, what I claim as new and useful is:—

In a device of the kind described, a polygonal driving shaft, journals mounted on said shaft, bearings in which said journals are mounted whereby the shaft may be revolved, a pair of sleeves mounted on said shaft adjacent each other and having flanges at their outer ends, means to secure said sleeves in place on the shaft, a bevel gear on each sleeve free to revolve thereon and held against outward endwise movement by the flanges, a bevel pinion between the gears and constantly in mesh with both of them which will prevent inward movement of said gears, a screw shaft on which the pinion is mounted, clutch teeth on the outer ends of said gears, clutch members mounted to revolve with and slide on the driving shaft, clutch teeth on the inner ends of said members for engagement with the teeth on

the gears for temporarily connecting a clutch member and gear to cause such gear to revolve with the shaft, forks engaging said clutch members, a longitudinally slidable rod on which said forks are mounted whereby the movements of said rod will simultaneously engage one clutch member with its respective gear and disengage the other clutch member from its respective gear, an arm projecting from said rod intermediate its ends, a shifting axle rotatable a one-half turn, a crank on said axle, a link having one end connected to said crank and the other end to the arm projecting from the sliding rod, said parts being

so arranged that the link and crank will be on dead center at the ends of the longitudinal movements of the sliding rod, a plunger having threaded connection with the screw shaft, a cam device carried by said plunger and including two cam members, and arms mounted on the shifting axle in spaced relation to be engaged by the cam elements for alternately rotating the shifting axle in opposite directions for reversing the direction of rotation of the screw shaft whereby the plunger will be reciprocated.
